UNITED STATES PATENT OFFICE

PHILIP L. KOPP, OF BURKSVILLE, ILLINOIS, ASSIGNOR OF ONE-HALF TO ALOIS J. KOENIGSMARK, OF WATERLOO, ILLINOIS

TRACK CROSSOVER FOR RAILROADS

Application filed April 4, 1929. Serial No. 352,485.

My invention relates to railway tracks and more especially to a crossover where the rails of one track cross the rails of another.

5 The primary object of my invention is to provide a railway crossover of such construction that the joints between the rails crossing one another will be strong and durable to withstand the traffic passing over 10 the same, and including guards or guides for the wheels of the cars passing said crossover in either direction, the rails forming the crossover in the present instance having sufficient body at the joints to reduce to 15 a minimum the wear at these points by practically eliminating vibration of the rails during the passing of a train thereover.

A further object of my invention is to 20 construct a crossover for railroad tracks that will have the required rigidity at the joints and yet provide for the use of the usual spikes or bolts in securing the rails to ties or a metal plate forming a platform for the crossover, with the ends of the 25 jointed rails constituting my invention shaped to join to the ends of ordinary rails for the continuation of the tracks.

Other objects and advantages of my invention will hereinafter appear in this 30 specification, and what I particularly claim as new and desire to protect by Letters Patent is specifically set forth in the appended claims.

In the drawings, forming a part hereof:—

35 Figure 1 is a plan view of a railway track crossover constructed in accordance with my invention.

Figs. 2 and 3 are sectional views on the lines 2—2 and 3—3 of Fig. 1, and

40 Fig. 4 is a transverse sectional view of Fig. 1 through the joints of the rails on a line with the groove to receive the wheel flanges of the railway cars.

Referring to the drawings, 5—5 and 6—6 45 designate the rails forming the crossover,

the rails 5 in the present instance representing those of the main line or track over which a greater amount of traffic passes and are of a slightly different construction at the joint to increase the stability of the 50 crossover structure, as hereinafter explained.

In carrying out my invention the rails 5 and 6 at the points where they cross one another are rectangular in cross section, being of a height corresponding with that 55 of the ordinary railroad rail and of a width to present a wide tread 5^a and 6^a, respectively, at the upper portion thereof with adjoining guard-rail portions 7 separated by longitudinal grooves 8 for the usual 60 wheel flanges of railway cars, the grooves of one set of rails bisecting those of the other and the guard-rails extended beyond the joints a suitable distance and beveled outwardly at their ends, as shown in Fig. 65 1 of the drawing. A lap-joint is formed between the crossed rails by opposite recesses in said rails respectively, the recess in the rail 6 being deeper than that in the main rail 5 to increase the body of said last mentioned rail at the joint, as shown in Fig. 4, it being noted that the portion 9 of rail 70 6 is below the recess in which the longitudinal portion 10 of rail 5 fits and that it rests directly on the support for the 75 crossover. Furthermore, it will be noted that by having the rails rectangular in cross section at the joint or joints and closely fitting the interlocking portions of said rails, a strong, rigid and durable joint is provided 80 to withstand the traffic passing the crossover in either direction, both rails having a wide bearing on the support to prevent vibration and reduce wear at the joint.

In order to lighten the rails, and more 85 especially for the purpose of securing the rails to the support on the roadway by means of the usual spikes 18 each rail is cut away centrally between the joints, as 90 at 11, and similarly cut away beyond the

joints, as at 12, in each instance leaving a bottom flange 13 corresponding with the usual bottom flange of the ordinary railroad rail over which the head of the spikes project in securing the rails in place, the cutaway portion at the inner side of each rail of the crossover terminating at a suitable distance from the end of the guide portion 7 to provide a solid portion 14 which increases the strength of the end of said guide portion. The end of each rail which projects beyond the guide portion is reduced in width so that it may be joined to the ordinary rails 15 by tie plates 16.

15 The crossover may be supported on the usual railroad ties (not shown) but in order to increase its stability a metal plate or platform 17 is placed under the same and provided with holes through which the spikes are driven into the ties, or bolts may be used instead of spikes, and although I have shown the crossover for single tracks the same arrangement may be carried out for double tracks; furthermore, instead of 20 having the tracks or rails 5 and 6 crossing each other at a right angle they may be constructed to cross at any angle desired by changing the formation or angle of the recesses at the interlocking joints.

25 From the foregoing description it will be readily seen that I provide a construction of crossover for railways in which the rails are shaped to not only provide a strong and rigid joint which will withstand heavy traffic but also provides for securing the crossover in place by means of the ordinary spikes or bolts and for connecting the rails constituting said crossover to ordinary rails for the continuation of the tracks, the increased width of the tread and base portions 30 of the rails of the crossover giving the desired weight or body at the points usually subjected to wear—that is at the joints and ends of the guard portions or guide-rails.

40 45 The construction of the crossover employing the rails of the particular construction herein shown and described can be easily laid after the manner of ordinary rails, and although I have illustrated the preferred 50 embodiment of my invention it will be understood that changes, such as hereinbefore suggested, may be made without departing from the spirit and scope of the appended claims.

55 I claim:

1. A crossover comprising solid rails rectangular in cross section where they cross each other at which point the upper portion of one rail and the lower portion of the other 60 are provided with rectangular recesses for interlocking engagement of the crossed rails to form a close-fitting lap joint, with the upper and lower surfaces of both rails in the same horizontal planes.

65 2. A crossover comprising solid rails rec-

tangular in cross section and provided with longitudinal grooves to receive the car-wheel rim-flanges and form guard portions extending upwardly with the thread portions of said rectangular shaped rails, the rails where they cross each other having rectangular recesses in the upper and lower portions thereof respectively to receive the crossed rails and form a close-fitting lap joint, with the upper and lower surfaces of both rails in the same horizontal planes. 70 75

3. A crossover comprising solid rails rectangular in cross section and provided with longitudinal grooves to receive the car-wheel rim-flanges and form guard portions or guide-rails extending upwardly parallel with the thread portions of said rails, the rails where they cross each other having rectangular recesses in the upper and lower portions thereof respectively to receive the crossed rails and form a close-fitting lap joint with the upper and lower surfaces of both rails in the same horizontal planes, said rails being cut away at opposite sides beyond the joints to reduce the weight of the same, 80 85 and provide base flanges for engagement of the spikes to secure the crossover in place. 90

4. A crossover comprising solid rails rectangular in cross section and provided with longitudinal grooves to receive the car-wheel rim-flanges and form guard portions or guide-rails extending upwardly parallel with the thread portions and beyond which the main portion of the rail projects and is reduced in width, joints for the crossed rails 95 formed by rectangular recesses in the upper and lower portions thereof respectively for interlocking engagement of the crossed rails, the opposite sides of the rails forming the crossover being cut away to reduce the 100 weight and provide base flanges for engagement of the spikes to secure the crossover in place. 105

5. A crossover comprising rails rectangular in cross section and provided with longitudinal grooves to receive the car-wheel rim-flanges and form guard portions or guide-rails extending upwardly with the thread portion and beyond which the main portion of the rail projects and is reduced in width, 110 joints for the crossed rails formed by opposite rectangular recesses for interlocking engagement of the rails, the opposite sides of the rails forming the crossover being cut away between the joints and beyond said 115 joints with the cutaway portions of the guard portions or guide-rails terminating near the ends of said guide-rails. 120

6. A crossover comprising rails rectangular in cross section and provided with longitudinal grooves to receive the car-wheel rim-flanges and form guard portions or guide-rails extending upwardly with the thread portion and beyond which the main portion of the rail projects and is reduced in width, 125 130

joints for the crossed rails formed by opposite rectangular recesses for interlocking engagement of the rails, the opposite sides of the rails forming the crossover being cut away between the joints and beyond said joints with the cutaway portions of the guard portions or guide-rails terminating near the ends of said guide-rails; together with a platform on which the crossover rests and to which it is secured.
